UNITED STATES PATENT OFFICE.

GROVER CLEVELAND TRUSLOW, OF DRAPER, NORTH CAROLINA.

MIXER.

1,399,590.

Specification of Letters Patent.

Patented Dec. 6, 1921.

Application filed May 14, 1921. Serial No. 469,440.

To all whom it may concern:

Be it known that I, GROVER C. TRUSLOW, a citizen of the United States, and a resident of Draper, in the county of Rockingham and State of North Carolina, have invented a new and Improved Mixer, of which the following is a full, clear, and exact description.

This invention relates to improvements 10 in mixers, particularly to an apparatus for mixing fibers.

An object of the invention is to provide a time and labor saving mechanism for mixing different classes of fibers, such as cotton 15 and wool, or fibers of various colors.

A further object is to provide a mixer of this character which will be simple and practical in construction, strong, durable 20 and efficient in use, and comparatively inexpensive to install and operate.

With these and other objects in view, the invention consists in certain novel features of construction and combinations and arrangements of parts as will be more fully 25 hereinafter described and pointed out in the claims.

In the accompanying drawings:—

Figure 1 is a sectional view through a mixing room or compartment showing my 30 improved mixer in elevation;

Fig. 2 is a view in longitudinal section through the mixer;

Fig. 3 is a view mainly in elevation with parts broken away for clearness, illustrating a slight modification;

Fig. 4 is a fragmentary sectional view of a modified form of deflector; and

Fig. 5 is a bottom plan view of the deflector illustrated in Fig. 4.

Referring in detail to the drawings, 1 represents the floor, 2 the ceiling, and 3, 3 the walls of a mixing room or compartment. Adjacent the center of the room, I provide an upright post or standard 4 rigidly attached to the floor by means of 45 braces such as 5. A short vertical shaft 6 is journaled in a bracket 7 carried by the upper end of the standard 4 and in suitable bearings designated by the reference numeral 8 in the upper end of the standard. 50 This shaft supports a revolving platform or table 9.

A drive shaft 10 is journaled in one side wall of the compartment and in a bracket 55 11 carried by the upper end of the standard

4. A beveled pinion 12 on the inner end of the drive shaft meshes with a beveled gear wheel 13 fixed to the shaft 6. The drive shaft 10 may be driven through the medium of a pulley 14 on its outer end and 60 a belt 15 which transmits power from any suitable source. The particular means of driving the shaft 10, however, is immaterial to this invention.

A feed pipe 16 extends through one wall 65 of the compartment and is formed with an elbow 17 and a short downwardly-turned vertical portion 18 which is in vertical alinement with the shaft 6. A distributing arm in the form of an L 19 is supported 70 upon the platform 9 and retained in place by suitable brackets 20. One end of the L is directly over the center of the platform and includes an upstanding flange 21 which receives the lower end of the extension 18 75 of the feed pipe. A balancing weight 22 at one end of the platform serves to offset the weight of the L 19 and prevent friction between the collar 21 and the depending portion of the feed pipe. A bracket 23 is 80 integral with a split collar 24 which encircles the collar or flange 21. The bracket 23 supports a deflector 25 directly above the open upwardly extending outer end of the L. The deflector 25 is preferably of the 85 conical shape illustrated.

A blast of air is introduced into the feed pipe 16 by any convenient fan or blower (not shown).

In Fig. 3, I have illustrated a slight 90 modification, wherein a bracket such as 26 is substituted in place of the bracket 23. At its outer end, a short vertical shaft 27 is journaled in the bracket and carries a deflector 28. Integral upwardly presented 95 bearing sleeves 29 form a part of the bracket 26. A horizontal shaft 30 is mounted in these sleeves. A beveled pinion 31 on the outer end of the shaft 30 meshes with a beveled pinion 32 on the 100 shaft 27 so that turning of the shaft 30 operates the shaft 27 and rotates the deflector 28. A beveled pinion 33 meshes with a stationary crown gear 34 around the depending extension of the feed pipe 35 so that as the 105 L 19 is revolved, the deflector which it carries will be rotated.

In Figs. 4 and 5, I have illustrated a deflector 35, which has bearings such as 36 in the end of a bracket 37. Radially curved 110

webs 38 are provided upon the inside of this deflector so that the air passing through the L 19 will engage these webs and cause the deflector to rotate.

5 The operation of the device is as follows:

The various forms of fibers to be mixed are introduced into the feed pipe 16. The blast of air through the pipe 16 will direct the fibers into the L 19 which is being constantly revolved through the medium of the shafts 6 and 10. As the fiber is blown out of the outer end of the L, it is driven against the deflector 25 and scattered about the floor of the compartment. With the forms of deflectors shown in Figs. 3, 4 and 5, the fiber is still further scattered and mixed by virtue of the fact that these deflectors are rotating above the outlet of the revolving L.

20 Although I have illustrated certain of the preferred embodiments of my invention, it will be apparent that various slight changes and alterations might be made in the general form and arrangement of the parts described without departing from the invention and hence I do not wish to limit myself to the precise details set forth, but shall consider myself at liberty to make such slight changes and alterations as fairly fall within the spirit and scope of the appended claims.

When the mixer is used in a closed chamber such as illustrated in Fig. 1 of the drawings, it will be necessary to provide a screened ventilator such as 39, to provide an outlet for the air flowing through the distributing arm.

I claim:

1. A mixer of the character described, including a feed pipe, a continually swinging hollow distributing arm communicating with the feed pipe, means for introducing a current of air and the material to be mixed into the feed pipe, means carried by the distributing arm for scattering the material discharged therefrom, said means comprising a conical deflector, and means for revolving said deflector.

2. A mixer of the character described, including a revolving L, a feed pipe adapted to convey air under pressure to the L, and a conical deflector supported above the air outlet end of the L.

3. A mixer of the character described, including a revolving L, a feed pipe adapted to convey air under pressure to the L, and a deflector supported above the air outlet end of the L, and means for rotating the deflector.

4. A mixer of the character described, including a table, means for revolving the table, an L supported on the table, means for introducing air under pressure and material to be mixed into the L, a rotating de-

flector at the outer end of the L adapted to scatter material discharged from the L.

5. A mixer of the character described, including a table, means for revolving the table, an L supported on the table, means for introducing air under pressure and material to be mixed into the L, a deflector at the outer end of the L adapted to scatter material discharged from the L, and means for rotating the deflector.

6. A mixer of the character described, including a feed pipe, means for introducing a current of air and material to be mixed into a feed pipe, a swinging distributing arm communicating with the feed pipe, and a rotating deflector at the discharging end of the distributing arm for scattering said material.

7. A device of the character described in claim 6 and including means whereby the air current passing through the distributing arm rotates the deflector.

8. A mixer of the character described, including a feed pipe, a swinging hollow distributing arm communicating with the feed pipe, means for introducing a current of air and material to be mixed into the feed pipe, means carried by the distributing arm for scattering the material discharged therefrom.

9. A mixer of the character described, including a feed pipe, a hollow distributing arm communicating with the feed pipe and continually swinging in a horizontal plane, means for introducing a current of air and material to be mixed into the feed pipe, means carried by the distributing arm for scattering the material discharged from the arm, said means comprising a conical deflector.

10. In a mixer of the class described, a mixing chamber, a standard in the chamber, a short vertical shaft journaled in the upper end of the standard, a platform supported upon said shaft, means for actuating the shaft to rotate the platform, a hollow distributing arm supported on the platform, a stationary feed pipe communicating with the distributing arm, a deflector carried by the arm and adapted to scatter material discharged therefrom.

11. In a mixer of the class described, a mixing chamber, a standard in the chamber, a short vertical shaft journaled in the upper end of the standard, a platform supported upon said shaft, means for actuating the shaft to rotate the platform, a hollow distributing arm supported on the platform, a stationary feed pipe communicating with the distributing arm, a deflector carried by the arm and adapted to scatter material discharged therefrom, and means whereby revolution of the arm rotates the deflector.

GROVER CLEVELAND TRUSLOW.
